CARTRIDGE FOR RECORD TAPE

Arnold J. Butler, Wappingers Falls, and Arnold M. Davis, Poughkeepsie, N.Y., assignor to International Business Machines Corporation, New York, N.Y., a corporation of New York

Filed June 27, 1960, Ser. No. 61,133

Term of patent 14 years

(Cl. D26—14)

FIG. 1

FIG. 2

Fig. 1 is a perspective view of the front and left hand side of a cartridge for record tape showing our new design.

Fig. 2 is a perspective view of the rear and right hand side thereof.

The diagonal lines on Fig. 1 indicate a transparent cover.

We claim:

The ornamental design for a cartridge for record tape, substantially as shown and described.
